UNITED STATES PATENT OFFICE.

ALLEN W. SHARP, OF OTTUMWA, IOWA, ASSIGNOR TO JOHNSTON PRESSED GEAR COMPANY, OF OTTUMWA, IOWA, A CORPORATION OF IOWA.

RUG-BEATING MACHINE.

Application filed October 4, 1923. Serial No. 666,445.

The present invention relates to a machine for cleaning rugs and the like and has more special reference to a machine of this character in which the cleaning is accomplished by a beating action whereby the dust and loose dirt is removed.

A principal object of the invention is the provision of a rug beating machine of automatic and efficient action and which does not require particular skill or detailed instructions for the operation thereof.

A further object is the provision of a machine for the purpose stated which is self-contained and in which the parts are arranged within the compass of a relatively small casing which may be readily transported to the desired place of operation.

Numerous other objects and advantages of the invention will be apparent as it is better understood from the following description, which, taken in connection with the accompanying drawings, discloses a preferred embodiment thereof.

Referring to the drawings,

Figure 1 is a side view of the machine, partially broken away for convenience in illustration;

Fig. 2 is an end view, also partially broken away;

Fig. 3 is an enlarged detail view of the spider, showing the means by which the straps are secured thereto;

Fig. 4 is a partial longitudinal section of said spider;

Fig. 5 is a still further enlarged partial plan view of the strap holding bar; and

Fig. 6 is a sectional view of said bar bent to the form in which it is used.

The machine which I have shown on the drawings, for purposes of illustration, comprises a casing 21 which is formed of sheet metal or the like and which is supported by rear wheels 22 and a steering wheel 23, a handle 24 being provided at the front of said casing and the operating parts being disposed within the casing, as will hereinafter appear.

The wheels 22 are supported upon short shafts 25, which extend through the casing and having bearings in brackets 26 depending from longitudinal frame bars 27 secured within said casing at the opposite sides thereof. Uprights 28 are secured to the frame bars 27 and support cross connectors 29 at the top of a sloping portion 31 of the

casing. Braces 32 extend from the outer ends of the bar 27 and are connected to the upper ends of the uprights 28, there being a longitudinal brace 33 extending between said uprights and connected thereto at the point of attachment of the braces 32. The handle 24 comprises upper bars 34 and lower bars 35 which are connected respectively at their inner ends to the frame bars 27 and the uprights 28, said bars extending outwardly at an angle and converging to a point 36 at which they are connected by a transverse rod 37.

A rectangular casing portion 38 is supported on the cross connectors 29 and provides a housing for a motor 39 and other parts, as will later be described. Said motor is supported by brackets 41 secured to said cross connectors 29. A motor shaft 42 carries at its outer end a small pulley 43, which is adapted to drive a belt 44 taking over a large pulley 45 carried on a transverse shaft 46 upon which the rug beating mechanism is mounted. An idler wheel 47 is mounted in arms 48 pivoted at 49 to one of the uprights 28 and is held in contact with the belt 44 to provide the desired tension thereon by means of a spring 51 secured at one end to an arm 48 and at the opposite end to an opposite upright 28.

The rug beating mechanism comprises a plurality of beater straps 52 secured to spiders 53, which are in turn secured to the opposite ends of the shaft 46 by means of pins 54, and side plates 55 extending between adjacent arms of said spider and being preferably formed of sheet metal, or other like material. A plate 56 is provided for each corner of the frame and is bent to a U-shape, as shown in Figure 6. Said plate is perforated, as indicated at 57, and is adapted to be held in place by means of bolts 58 extending through the edges 59 of the plates 55 and through the ends of the spider arms, as clearly shown in Fig. 3. The plates 56 are provided with spaced series of slots 61 which are disposed at the bend when said plates are in position. Rods 62 are adapted to extend through the U-plates beyond the ends of the spider arms, and laces 63 are employed to bind the straps 52 onto said rods 62, it being obvious that said straps may extend through the slots 61 in the plate 56. In this manner, the straps 52 are firmly secured to the drum and it will be obvious

- that, upon rotation of the latter, said straps are caused to strike a rug upon which the machine may be positioned. Said straps, while preferably relatively heavy and of sufficient stiffness to cause them to be normally projected, as shown in Fig. 1, are bent by contact with the rug, as clearly illustrated at the bottom of said figure. The straps, at the different corners of the drum, are arranged in staggered relationship and when said drum is driven by the motor 39, the entire width of the rug between the ends of the drum is subjected to a violent beating action which will cause the dust and dirt to be freed, in the well-known manner, a fan 64 being provided on the motor shaft 42 and adapted to draw the dirt through an opening 65 and into a receptacle 66 of any preferred form, positioned in the end of the upper casing 38.
- The machine may be readily transported from one position to another, so that the entire rug surface may be subjected to beating and also in order that the machine may be moved from place to place. The handle 24 is disposed at a convenient height so that the machine may be pushed or drawn, as desired, the steering wheel 23 being disposed in advance of the casing 21 and being movable about a vertical axis provided by a bearing 67 secured to the outer end of a frame bracket 68. Said wheel is held in a yoke 69 provided with an upwardly extending stud 71 adapted to fit within a socket in the bearing member 67 after the fashion of a caster. The plates 55 and the two spiders 53 form a drum, mounted for rotation in the frame composed in part of the bars or plates 27, 28 and 29.
- The described mechanism obviously performs its function in wholly automatic manner and with rapidity and efficiency which is not possible with the usual methods employed. The machine may be used in cleaning establishments, or may be readily adapted for individual use, as desired.
- It is thought that the invention and many of its attendant advantages will be understood from the foregoing description, and it will be apparent that various changes may be made in the form, construction and arrangement of the parts without departing from the spirit and scope of the invention, or sacrificing all of its material advantages, the form hereinbefore described being merely a preferred embodiment thereof.
- I claim:
1. In a rug beating machine, the combination of a frame, a plurality of bearings carried by said frame, said bearings having wheels mounted thereon, a plurality of upstanding brace members carried by said frame said brace members forming an upper platform, a motor mounted on said platform, including a shaft extending transversely across said platform, a pulley on one end of said shaft, a fan on the other end of the motor shaft, a casing surrounding said motor, a portion of said casing having walls forming an opening adapted to receive a bag and being opposite said fan, said casing extending downwardly substantially to the floor whereby to form a closed suction chamber, a shaft mounted in the lower portion of said casing and having a pulley under said first-mentioned pulley, spiders mounted on said last mentioned shaft within said casing, and a plurality of flexible rug beating elements mounted on said spiders, a belt extending around said pulleys where by on rotation of the motor shaft said rug beating elements will be slapped into engagement with a rug.
  2. In a rug beating device, the combination of a movable frame, an enclosing casing forming a beating chamber and being open at the bottom, a transverse shaft mounted on said frame, a spider on said shaft and having a plurality of arms, each arm of said spider terminating in a flange, relatively elongated clips U-shaped in cross section extending substantially the length of said shaft, said clips being perforated for attachment to the extremities of said arms by means of a bolt passing therethrough, the U-portion of the clips being slotted and a plurality of flexible rug beating elements having perforations adapted to receive fastening elements therethrough and extending through the slots in the clips and a detachable rod passing through the U-portion of each clip and through said fastening elements to hold them in position, and means to rotate said shaft.

ALLEN W. SHARP.
